UNITED STATES PATENT OFFICE.

ORRIN W. ORCUTT, OF ST. JOHNSBURY, VERMONT.

POWER-HAMMER.

SPECIFICATION forming part of Letters Patent No. 503,492, dated August 15, 1893.

Application filed April 20, 1891. Serial No. 389,700. (No model.)

To all whom it may concern:

Be it known that I, ORRIN W. ORCUTT, a citizen of the United States, residing at St. Johnsbury, in the county of Caledonia and 5 State of Vermont, have invented a new and useful Power-Hammer, of which the following is a specification.

My invention relates to certain improvements in power-hammers wherein a vertically reciprocating hammer operates in conjunction with a fixed anvil; and it consists in the combination and arrangement of the various parts as will be hereinafter more fully described in the specification and specifically 15 set forth in the claim.

The objects of the invention are, first, to provide an adjustable crank-pin whereby the length of stroke may be adjusted independently of the hammer, and the force of the 20 blow varied, and second, to provide cushions for the hammer and means for securely connecting said hammer, through the cushions, to the crank, whereby shock is prevented from being communicated to the crank. These objects are attained by the mechanism illustrated in the accompanying drawings, in 25 which—

Figure 1 represents an elevation of my improved machine; Fig. 2, a detail sectional view, showing the various adjustments, and 30 Fig. 3, a detail sectional view of the sleeve-sleeve.

Similar letters refer to similar parts throughout the several views.

35 The letter A indicates the crank-plate mounted on the shaft *a*, journaled in suitable bearings (not shown) in the frame of the machine. Pivoted to the crank-plate is an adjustable crank-disk, B, formed with a semi-circular slot, *b*, and a crank-pin D. A clamping-bolt, C, serves to secure the crank-disk onto the crank-plate, which is counterbored 40 to receive it, and to hold the same rigidly in place until said bolt is loosened. The plate A 45 may be provided with a bundle A² by which it may be held, while the crank plate B is shifted, to adjust the stroke of the hammer operating mechanism.

Connected to the crank-pin D is a connecting-rod, E, carrying a sleeve, F, provided with 50 a housing for receiving the springs J' and J² which are coiled around bosses c' and c², respectively, the short end of spring J' being

securely fastened by set-screw M' and that of J² by set-screw M². The sleeve F is rigidly 55 held onto the connecting-rod by means of a clamping device, which consists of a collar, f, and a bolt G. The hammer N is connected to the lower end of the springs J' and J², which are jointed, by links L' and L², respectively. The hammer reciprocates in guides O, O, formed in the frame of the machine, said guides being on a line perpendicular with the center of the crank-plate and anvil-block Q. The springs are coiled in line with the strain 65 or work, so that they will wind and unwind and not compress lengthwise the coiled section. The springs exert a pressure which tends to hold the links in a nearly horizontal position, so that any downward movement of 70 the hammer, which throws the links below the horizontal line, will tend to wind up said springs, increasing their force and causing the links to again assume an approximately horizontal position.

75 The operation of the machine will be readily understood in connection with the above description, and is as follows: As the crank plate is revolved it carries the crank disk with it, giving a reciprocating movement to 80 the rod E and sleeve F, and a similar movement to the hammer. To change the length of stroke of the hammer, the bolt C is loosened and the disk B turned in the proper direction and when in proper position it is fastened to the crank plate by clamping the bolt C.

Having thus fully described my invention, what I claim as new, and desire to secure by 85 Letters Patent, is—

90 In a power hammer, the combination with a crank plate mounted on a driving shaft, and an adjustable disk and adjusting devices mounted on the crank plate, of a connecting rod secured to the pin of the crank disk, the 95 double springs secured to the shoulders of the sleeve on the connecting rod, and connected to the hammer, and the set screws bearing against the free ends of the springs, whereby their tension may be regulated, substantially 100 as specified.

ORRIN W. ORCUTT.
